UNITED STATES PATENT OFFICE.

HARRY E. WADSWORTH, OF NEW YORK, AND WILLIAM B. ENSIGN, OF WHITE PLAINS,
NEW YORK.

AUTOMATIC ELECTRIC-CIRCUIT BREAKER.

1,359,298.

Specification of Letters Patent. Patented Nov. 16, 1920.

Application filed January 12, 1920. Serial No. 350,966.

To all whom it may concern:

Be it known that we, HARRY E. WADSWORTH, a citizen of the United States, and a resident of the borough and county of Bronx, city and State of New York, and WILLIAM B. ENSIGN, a citizen of the United States, and a resident of White Plains, county of Westchester, and State of New York, have invented certain new and useful Improvements in Automatic Electric-Circuit Breakers, of which the following is a specification.

Our improvements relate to means for automatically breaking or opening an electric circuit when a predetermined excess of current occurs, substantially as set forth in our concurrent application Serial No. 314,552, filed July 31, 1919, the object, as in that case, being primarily to dispense with cut-out fuses by providing an equivalent therefor to be positioned in like manner between the usual spring clip terminals; to effectually protect the operative parts and prevent tampering therewith, etc.—our invention in the present case consisting in the construction, combination and arrangement of parts herein described and claimed specifically, whereby these desired results are attained; and a distinctive feature in the present case being the trip lever mechanism employed to effect a forceful and instantaneous break of circuit whenever the latter exceeds a prescribed intensity, as well as the employment of knife blade contacts, in conjunction with a contactual rock lever, whereby the contact breaks are multiplied and spark danger thereby lessened, all as hereinafter fully set forth.

In the accompanying drawings,

Figure 1, is a front elevation of our improved circuit breaker;

Fig. 2, is an end elevation thereof;

Fig. 3, is a front view of our circuit breaker as mounted between knife blade circuit terminals;

Fig. 4, is a central longitudinal sectional elevation taken substantially upon plane of line 4—4, Fig. 1, showing the operative parts as set when the electric circuit is closed;

Fig. 5, is a like view showing the contactual rock lever tripped as when the circuit is broken;

Fig. 6, is a view like unto Fig. 4, illustrating the resetting operation;

Fig. 7, is a sectional elevation taken upon plane of line 7—7, Fig. 4.

The casing of insulating material is made in two parts C, C', each forming one half of the basic structure, and each being substantially a reversed duplication of the other. The extremities of each half are semi-circular, so that when the halves are fitted together cylindrical ends are formed over which the cylindrical metallic ferrule caps F, F', fit, binding the two said non-conductive parts C, C', of the housing together. These parts C, C', are further secured together by the rigidly mounted cross bar B, and further, if desired, by screws or bolts for which holes c, c, may be provided as indicated in Figs. 4, 5 and 6.

One of the ferrule caps, F, is a fixture upon its end of the casing C, C', being rigidly attached thereto by any suitable mechanical expedient,—while the other ferrule cap F', is movable within certain prescribed limits on its end of the casing for the purpose of re-setting the operative parts, as hereinafter set forth, after a "break" in the electric circuit. The ferrule caps F, F', may be adapted for insertion between either spring circuit terminal clips as in Fig. 2, or for engagement with knife blade circuit terminals, as in Fig. 3, in which latter view the device is shown as adapted to either form of terminal connection.

The medial portions of the halves C, C', of the non-conductive casing are formed with coincidental lateral extensions C^x, and are recessed to afford operative space for the contactual rock lever R, which is fulcrumed centrally on the cross bar B, aforesaid. That is to say, the metallic contacts m, m', mounted on the arms r, r', of the rock lever are equidistant from the fulcrum thereof,—the body of the lever itself being made of hard fibrous or other suitable non-conductive material. A spring a, tends constantly to draw the rock lever R, into the vertical position shown in Fig. 5, with its upper arm r, resting against a stop a', provided for the purpose. The lower arm r', of the rock lever R, is of segmental shape, and is formed with a bearing shoulder r², for engagement with the free end of a latch arm e, as shown in Figs. 4 and 6, said latch arm e, being pivotally supported at e', and being held normally against a stop e², by a spring e³. The lower arm r', of the rock

lever R, is also formed with a transverse slot r^3 , for the accommodation of a lateral projection d , on the free end of a retractor link d' , the other end of which is pivotally connected to a slide f' , rigidly secured to the movable ferrule cap F'—the parts C, C', being recessed to accommodate and support said slide f' .

Also rigidly attached to the movable ferrule cap F' is the bifurcated terminal f^2 , likewise supported slidably in coincident recesses in the opposed faces of the two parts C, C', of the casing.

Pivotedly supported at b' , on the same fulcrum as that of the latch arm e, is the trip lever t, formed with a kick off toe t', for contacting with the said latch arm e, when the trip lever t, is actuated by the electro-magnet M.

20 The winding of the electro-magnet M, is included in the electric circuit, so that any intensity of current over a prescribed degree will cause its core to attract and pull over the trip lever t, against the resistance of the retractile spring t^2 , which tends constantly to hold said trip lever t, against a stationary part, as for instance, the protuberant stop c', on the casing.

25 k, k' , are terminal clips, one of which is in electrical connection with the stationary ferrule cap F, the other with the circuit wire from the electro-magnet M, so that in the absence of the metallic knife blade contact m, between said terminal clips k, k' , the 30 circuit is broken.

30 The operation is as follows:—The parts being in the relative positions shown in Fig. 4, with the circuit passing between ferrule caps F, F', from one to the other through the bifurcated terminal f^2 , contact m' , electro-magnet M, terminal clips k, k' , and contact m, as under prescribed normal conditions, any abnormal increase of current will energize the electro-magnet M, sufficiently 35 to suddenly pull the trip lever t, over toward it against the resistance of the spring t^2 . As a result the kick off toe t', impinges with force against the latch arm e, knocking it out of engagement with the bearing shoulder r^2 , against the resistance of the spring e^3 , thereby allowing the spring a, to rock the lever R, into the position shown in Fig. 5, with its upper arm r, resting against the stop a' . This of course withdraws the metallic contact m, from engagement with the terminal clips k, k' , and the metallic contact m' , from engagement with the bifurcated terminal f^2 , simultaneously, thus opening the circuit.

40 To re-set the parts the device is removed bodily from the main circuit terminal connections, and the movable ferrule cap F', is partly withdrawn from its normal position, on its end of the casing, the motion being 45 limited by a stop s, or otherwise. The open-

ing of the circuit has of course de-magnetized the electro-magnet M, so that the spring t^2 , has returned the trip lever t, to normal position against the stop c' , thereby allowing the spring e^3 , to return the latch arm e, to its normal position, resting against the stop e^2 . Hence, when the aforesaid partial withdrawal of the movable ferrule cap F', takes place, causing the retractor link d' , to draw the contactual rock lever R, back into normal position against the resistance of the spring a, the bearing shoulder r^2 , in passing will depress the free end of the latch arm e, slightly against the resistance of the spring e^3 , which latter will then return the latch lever to normal position against its stop e^2 , with the free end of said latch arm e, again in engagement with the said bearing shoulder r^2 , on the rock lever R, as shown in Fig. 6, thus locking said rock lever 50 in contactual position, with its upper metallic contact m, between the terminal clips k, k' , and its lower metallic contact m' , in position for engagement with and between the arms of the bifurcated terminal f^2 ; when 55 the ferrule cap F', is again returned to its normal position on its end of the casing, thus restoring all the parts to reset closed-circuit relationship, so that when the device is re-inserted between the main circuit 60 terminals the electric current will be free to pass as long as it does not again exceed a degree of intensity prescribed by the winding of the coil on the electro-magnet M.

65 By thus providing for the use of knife 100 blade make and break connections we minimize the intensity of arc flash by subdividing and distributing it, so that the sparking is rendered comparatively harmless.

70 As in the case of our cut-out slide circuit breaker described in said concurrent application Serial No. 314,552, it will be seen that in our present device the switch latch may be reset, when the device is removed from between the terminal clips, without opening 75 the casing, and by the simple expedient of reciprocating a portion thereof.

75 Furthermore all the operative parts of the circuit breaker are inclosed, isolated and protected from contact with extraneous 80 objects, and they cannot be tampered with or improperly manipulated while the incasement is intact. The device is an effectual substitute for the "blow-out" fuse, with the great advantage that it can be reset and used indefinitely; and the act of resetting simply involves its removal from 85 between the circuit terminal clips and the manipulation of the ferrule cap F', after which it is ready for replacement in operative position.

85 What we claim as our invention and desire to secure by Letters Patent is,

90 An automatic electric circuit breaker of the character designated, comprising a cas-

ing of insulating material, metallic ferrule caps formed externally for contactual engagement with main electric circuit terminal spring clip, internal electric clip terminals connected with each of said ferrule caps, a rock lever of non-conductive material on which are mounted metallic closure contacts for engagement with said internal spring clips, means which tend constantly to rock said contactual lever out of engagement with said internal electric terminal clips, a spring latch arm adapted to lock said rock lever in

normal position, a trip lever adapted to unlock said spring latch arm, an electro-magnet interposed in the circuit and adapted to actuate said trip lever, and ferrule-connected means for re-setting the parts after a break of the circuit, for the purpose described. ¹⁵
